UNITED STATES PATENT OFFICE.

JOHN E. ERICKSON, OF ST. PAUL, MINNESOTA, ASSIGNOR, BY DIRECT AND MESNE ASSIGNMENTS, TO AUTOMATIC SEATING COMPANY, OF SUPERIOR, WISCONSIN, A CORPORATION OF WISCONSIN.

AUTOMATIC FOLDING SEAT CONSTRUCTION.

Application filed May 14, 1921. Serial No. 469,561.

To all whom it may concern:

Be it known that I, JOHN E. ERICKSON, a citizen of the United States, residing at St. Paul, in the county of Ramsey and 5 State of Minnesota, have invented certain new and useful Improvements in Automatic Folding Seat Constructions, of which the following is a specification.

My invention relates to automatic folding seat constructions. It is intended particularly for use in connection with seats such as theater chairs and school chairs and benches, such as are commonly used out of doors. An object is to provide a construction in which the seat member is automatically folded or lifted when not held down and in which the weight of the person when sitting down causes the seat member to assume the proper position for supporting his 10 weight. In places where it is desirable that unoccupied seats should be lifted, my construction does not require any manual folding or lifting when the seat is not in use. This is of especial advantage in the use of 15 theater-seats since the unoccupied seats when my invention is used are always back out of the way to permit easy passage of persons going to or from their seats and, when the occupant of a seat rises to permit 20 the passage of other persons, the seat automatically folds or lifts so that he can move back sufficiently to permit other persons to pass. In the case of school seats or other chairs placed adjacent a desk or table, when 25 the occupant rises, his seat automatically folds and the person has easy passage to and from the seat. In the case of benches such as park benches, the seat members on account of not being in horizontal position 30 when unoccupied, will be kept much cleaner since there is not only less opportunity for dirt to collect or be deposited thereon but the action of rain will wash them more effectively. The use of my automatic folding 35 chair construction permits the occupants of the chairs to pass out much more quickly which is of especial advantage in case of fire in theatres, schools, and other public auditoriums.

50 The full objects and advantages of my invention will be apparent from the foregoing description, and the novel features embodied in my inventive idea will be particularly pointed out in the claims.

In the accompanying drawings, Fig. 1 55 is a side elevational view of a chair provided with my invention. Fig. 2 is a view in central section through the chair with the seat member in depressed position. Fig. 3 is a view similar to Fig. 2 but showing the 60 seat member in folded position. Fig. 4 is a view in vertical section on the line 4-4 of Fig. 5. Fig. 5 is a front elevational view with the seat member in depressed position. Fig. 6 is a view in horizontal section on the 65 line 6-6 of Fig. 5. Fig. 7 is a front elevational view of a bench provided with my invention. Fig. 8 is a side elevational view thereof. Fig. 9 is a view in section on the line 9-9 of Fig. 7. Fig. 10 is a top plan 70 view of one of the devices removed from the bench.

Referring first to the embodiment of the invention shown in Figs. 1 to 6, the numeral 12 designates in general the frame of 75 a theater chair having the customary arms 14 and a back 16 extending up from a lower vertical portion 18. In carrying out my invention, I provide a casting or other suitable metallic member 20 adapted to be secured in suitable manner to the lower portion 18. Secured to the lower side of the seat member 22 is a casting or other suitable metallic member 24. A link member 26 which may, for convenience, be made in 80 the form of a cross as shown, connects ears 28 on the front of the casting 24 with ears 30 formed near the lower end of the casting 20. A link member 32 connects ears 34 on an intermediate portion of the casting 85 24 with ears 36 on the upper end of the casting 20. As best shown in Figs. 3 and 6, the link member 32 is preferably formed with two side portions 38 intermediately connected by a shorter slightly depressed 90 portion 40 so that a rearward extension of the casting 24 may be received in the depression when the seat member is in lowered position as shown in Fig. 2. At 95 the rear of the connecting portion 40 the side members 38 are depressed to form the offset portions 42, these being the portions which are directly pivoted to the ears 36. On account of this construction and on account of the fact that when the seat member 100 is in its lowered position, the rear thereof is spaced from the back member, liability of the occupant of the chair getting his 105

2
fingers pinched is avoided. A rod 44 is pivotally attached at its upper end to ears 46 connected to the rear of the depressed portion 40 of the link member 32. The rod 44 is surrounded by a coiled spring 48 and this rod and spring are adapted to work in a tube or barrel 50 which is pivotally attached at its lower end to ears 52 on the lower end of the casting 20. When the seat 10 is not occupied or otherwise held down, the action of the spring 48 forces the rod 44 upwardly and, by means of the link member 32, causes the seat member to assume the position shown in Fig. 3, the movement 15 of the front of the seat member being restrained by the link member 26.

Referring to the form of invention shown in Figs. 7 to 10, the numeral 54 designates end frame members of a bench connected 20 by slats 56 which form the back and by lower slats 58. In applying my invention to a bench, I prefer on account of the length thereof to apply one of my operating devices at each end thereof. Since these two 25 devices are exactly alike, a description of one of them will be sufficient. A metallic member 60 is secured to the lower slats 58 in suitable manner. Secured to the lower side of the seat member 62 is a metallic member 30 64. A link member 66 preferably in two parts and meeting each other at the top as shown in Figs. 7 and 10 connects pivots 68 on the front of the member 64 with a pivot 70 on the lower end of the member 60. A 35 link member 72, the rear portion 74 of which is downwardly offset, connects a pivot 76 on the rear of the member 64 with a pivot 78 on the upper end of the member 60. A rod 80 is supported at its lower end on the 40 pivot 70 and the upper end of this rod extends slidably into a tube 82, which at its upper end, is pivoted to a lug 84 secured to the offset portion 74 of the link member 72. Surrounding the rod 80 and interposed 45 between a shoulder on the lower end thereof and the lower end of the tube 82 is a coiled spring 86. When the seat is not occupied or otherwise held down, the action of the spring 86 forces the tube 82 upwardly and, 50 by means of the link member 72, causes the seat member to assume the position shown in Fig. 9, the movement of the front of the seat being restrained by the link member 66. As shown in Fig. 8, the rear of the seat 55 member when depressed is spaced from the back so that there is no liability of the occupant getting his fingers pinched when he sits down.

The operation and advantages of my invention will be obvious from the foregoing 60 description. The principle of operation whether embodied in chair form or bench form is precisely the same but the bench on account of its length is preferably provided 65 with one of the devices at each end. It will

be noted that the seat member when not occupied is in an inclined position with the rear end highest. Therefore, the mere act of sitting on the seat readily brings it into proper position for supporting the occupant. 70

I claim:

1. A folding seat construction comprising a frame and back portion rigidly connected with said frame, a seat member, a pair of links pivotally connected at their lower ends 75 at spaced points to said frame in substantially a vertical plane with the lower end of said rigid back portion and pivoted at their forward ends at spaced points to the seat toward the front thereof, said links being substantially parallel and the last named pivots located substantially forwardly of the back frame when the seat is unoccupied, and spring means for action upon said links to lift the seat when the same is unoccupied. 80

2. A folding seat construction comprising a frame and back portion rigidly connected with said frame, a seat member, a pair of links pivotally connected at their forward ends to spaced points toward the front of 90 the seat and at their other ends at spaced points in substantially a vertical plane to said frame, and a third link pivoted to one of said links and to the frame in the plane of pivoting to the frame of the first-named 95 links, and spring means associated with the third link for acting upon the first-named links to cause them to fold said seat when the same is not occupied.

3. A folding seat construction comprising 100 a frame and back portion rigidly connected to said frame, a seat member, a pair of links pivotally connected at their forward ends to spaced points toward the front of the seat and at their other ends at spaced points 105 in substantially a vertical plane to said frame, the upper of said links having two offset portions with a right-angled connection, and a third link pivoted at its upper end to said connection and at its lower end 110 to the frame in the plane of pivoting to the frame of the first-named links, and spring means associated with the third link for acting upon the first-named links to cause them 115 to fold said seat when the same is not occupied.

4. An automatic folding seat construction comprising a frame, a seat member, two link members connecting said frame and said seat member and pivotally attached thereto, a third member connecting said frame and said seat member and pivotally attached thereto, and a spring associated with said third member which causes said seat member to assume a folded position 125 when unoccupied.

In testimony whereof I hereunto affix my signature.

JOHN E. ERICKSON.
